UNITED STATES PATENT OFFICE.

ARTHUR H. PFAFF, OF ELYRIA, OHIO.

HOLDER FOR SPINNING TOPS.

Application filed July 28, 1927. Serial No. 208,038.

This invention relates to a handle and holder for use in spinning tops, and the general object of the invention is to provide a handle and holder which may be used in spinning any form of top having an axial prolongation or an axial support.

A further object is to provide a handle and holder for top spinning which may be held in either the right hand or the left hand and which will guide the top cord properly with relation to the top and prevent any binding of the top cord, and which will further act so that the top will be slightly raised when the cord is pulled to spin the top.

A still further object is to so construct the holder that it may be very easily drawn away from the top so as to leave the top spinning upon its support.

Another object is to provide a holder which may be used with either side upward so that no special care has to be taken that the holder shall be held in exactly the right position.

Other objects will appear in the course of the following description.

My invention is illustrated in the accompanying drawing, wherein:—

Figure 1 is a top plan view of a top holder constructed in accordance with my invention;

Figure 2 is a side elevation thereof;

Figure 3 is a like view to Figure 2 but looking from the opposite side;

Figure 4 is an end elevation of the holder;

Figure 5 is a sectional view through the holder showing the manner in which the top is supported;

Figure 6 is an elevation of a top holder of a somewhat modified form from that shown in Figure 1.

Referring to this drawing, 10 designates my spinning device generally. This spinning device consists of a head 11 which constitutes the top holder and a handle 12. The head 11 is formed with a central opening or bore 13 which extends down through the head at right angles to the handle, this opening having an internal diameter preferably of about $\frac{11}{16}$ ", though I do not wish to be limited thereto. This opening opens onto the end face 14 of the head by means of a throat 15 having a width approximately half the diameter of the opening or bore 13 and extending vertically downward through the head from top to bottom.

The side faces of the head 11 are formed

each with two laterally extending bores 16 and 17. The bore 16, which is nearest to the handle, on one side of the head is lower than the bore 17 and extends downward toward the bottom of the head, while the bore 17 extends upward at an inclination, each of these bores opening upon the inner face of the opening 13 tangentially to the wall of the opening. The innermost bore 16a on the other side of the head is exactly the same as the bore 16, except that whereas the bore 16 extends downward and inward, the bore 16a extends upward and inward, while the bore 17a instead of extending upward and inward extends downward and inward. When the head is reversed, however, it will be seen that the bores 16a and 17a will occupy exactly the same position as previously occupied by the bores 16 and 17.

The handle is preferably formed integral with the head and may be about 4" long. The bores 16 and 17 and 16a and 17a are preferably about $\frac{3}{16}$ " in diameter more or less and the bores 16 and 16a are about $\frac{1}{4}$ " more or less from the handle end face of the head and from the upper or lower faces of the head respectively. The central opening 13 is preferably about $\frac{11}{16}$ " in diameter and the head itself is approximately about $1\frac{1}{8}$ " in length and approximately the same in width and about $\frac{7}{8}$ " thick. While I have stated these dimensions, it will be understood that the dimensions may be changed. These dimensions, however, I find are best for a holder designed to be used with ordinary tops.

In the use of this device, if the device is held in the left hand, then take one end of the top string with the right hand and run through the hole 16 or 16a nearest the handle. When holding the handle in the right hand, however, the top cord is to be run through the hole furthest from the handle with the left hand. In either case, the string is drawn up through the opening 13 far enough so that the string can be wound around any top, making about eight turns more or less in the usual manner. After winding the cord upon the top, the other end of the cord is pulled back so as to take up slack, holding the last turn of the cord which is wound on the top so that the cord will not unwind from the top. As the slack is taken out of the cord, the spur of the top is set in the opening 13, with the cord wound around so that the last winding on

the top will be near the hole 16 or 17 or 16^a or 17^a through which the cord is run. The handle is held with the top setting in the opening 13 about 6 to 8 inches more or less from the place where the top is to be spun. A quick pull of the cord which runs through the hole in the side of the holder will start the top spinning and about the same time the handle holder pulled out from the spur of the top and the top will spin by itself.

The reason for drilling two pairs of holes 16 and 16^a and 17 and 17^a in each side of the holder is that any top can be spun with the handle holder either in the left or right hand. The provision of the two holes 16 and 17 or 16^a and 17^a with the angular direction given to these holes is a considerable improvement over holders having one hole drilled through the middle of the head and intersecting a central spur-receiving opening, for the reasons that first, when running string through any of these holes drilled at the angles stated, the string will come out the top of the hole in the center of the holder and can be easily threaded in this manner, and second the two holes in either side of the holder provide means whereby either side of the head 10 can be disposed upward. Third, the two holes extending inward from each side of the holder are disposed so as to nearly intersect and extend nearly tangential to the wall of the bore or hole 13 so that when the string unwinds from the top, the string will not bind at this point, the string acting to slightly raise the top so that the handle and holder can be very easily drawn away from the top. The slot or throat 15 permits the handle and holder to be readily drawn away from the top after it is set spinning without retarding the spinning of the top at all.

In Figure 6 is shown a slightly modified form of the structure shown in Figure 1, in that the opening 13 is not formed with a throat 15 but the opening is entirely closed. Otherwise than this, the head 11 and the handle 10 are constructed in the same manner as shown in Figure 1 and the holes 16 and 16^a and 17 and 17^a extend through the head 11 in precisely the same manner as shown in Figures 1, 2 and 3.

I claim:—

1. A top holder of the character described comprising a head and a handle extending therefrom, the head having flat upper and lower faces and flat side faces and having a spinning top-spur receiving opening or bore extending from the top to the bottom face, the head on each side being formed with oppositely inclined bores extending

through the side walls of the head and intersecting the central bore and extending tangential to the wall of the bore.

2. A top holder of the character described comprising a head and a handle extending therefrom, the head having flat upper and lower faces and flat side faces and having a central spur-receiving opening extending from the top to the bottom face, the head on each side being formed with oppositely inclined bores extending through the side walls of the head and intersecting the central opening tangentially to the peripheral face of the opening, one of said bores being disposed adjacent the handle and extending downward and inward to intersect the opening through the head, another of said bores being disposed adjacent the other end of the head and extending upward and inward and intersecting the central opening of the head.

3. A top holder of the character described comprising a head and a handle extending therefrom, the head having flat upper and lower faces and flat side faces and having a central spur-receiving opening extending from the top to the bottom face, the head on each side being formed with oppositely inclined bores extending through the side walls of the head and intersecting the central bore, one of said bores being disposed adjacent the handle and extending downward and inward to intersect the opening through the head, another of said bores being disposed adjacent the other end of the head and extending upward and inward and intersecting the central opening of the head, the central opening of the head having a throat extending through to the end of the head remote from the handle.

4. A top holder of the character described comprising a head, a handle extending therefrom, the head having flat upper faces and flat side faces and having a central spur-receiving opening extending from the top to the bottom face of the head, the material of the head extending entirely around said bore, the head on each side being formed with oppositely inclined bores extending through the side walls of the head and intersecting the central bore, one of said bores being disposed adjacent the handle and extending downward and inward to intersect the opening through the head, another of said bores being disposed adjacent the other end of the head and extending upward and inward and intersecting the central opening of the head.

In testimony whereof I hereunto affix my signature.

ARTHUR H. PFAFF.
